UNITED STATES PATENT OFFICE.

JAMES FALLOON, OF NORTH BAY, ONTARIO, CANADA.

ANGLE-COCK FOR AIR-BRAKE SYSTEMS.

No. 893,614.

Specification of Letters Patent. Patented July 21, 1908.

Application filed November 13, 1907. Serial No. 401,971.

To all whom it may concern:

Be it known that I, JAMES FALLOON, of North Bay, in the district of Nipissing, Province of Ontario, Canada, have invented 5 certain new and useful Improvements in Angle-Cocks for Air-Brake Systems, of which the following is a specification.

My invention relates to improvements in angle cocks for air brake systems, as employed 10 on railway trains, and the objects are to improve the present form of angle cock, by providing means which will automatically throw the air brake into operation if the cock should be tampered with, left closed, or moved from 15 the open position in train line service, a further object being to provide such means as will gradually open the train line service, and so prevent the application of the emergency 20 brake.

In its construction, the invention includes the ordinary casing and plug, only the plug is provided with a port in the side thereof, and the casing has a corresponding port which is 25 gradually enlarged in the direction of the rotation of the plug, whereby if the plug is rotated to closed position, the interior of the angle cock will be placed in free and clear communication with the open air.

The invention is described more particularly in detail in the accompanying specification and drawings in which,

Figure 1 is a vertical longitudinal section through the angle cock. Fig. 2 shows a side view of the same. Fig. 3 is a perspective view 35 of the plug. Fig. 4 is a sectional detail along the line 2—2 Fig. 1.

In the drawings like letters of reference indicate corresponding parts in each figure.

Referring to the drawings, A is the angle 40 cock of the usual construction, having the plug B therein, with a passage-way a therethrough. In accordance with my invention a port b is provided in one side of the passage-way, adapted when the plug is rotated to 45 closed position, to afford communication between the train line pipe on one side and the passage-way a. The passage-way itself, when rotated, will be in communication with a port c provided through the side of the 50 casing. This port is gradually enlarged in the direction of rotation of the plug, whereby, as the plug is rotated, the port in the casing,

will be gradually unclosed, preventing such a rapid escape of air as would operate the emergency brakes. In the particular embodiment illustrated, the port c is triangular 55 in form.

In operation, when the cars are connected in train line service, the arrangement of the angle cock, will be as indicated in Fig. 1, the passage-way a permitting the free passage of air. Should, however, the angle cock be tampered with, and the plug rotated by the handle d or other means, the train line pipe on one side of the angle cock will be 60 placed in communication with the open air through the port c, the passage-way a and the port b, the opening of the port c being gradual, owing to its peculiar shape.

It will be observed that I have provided 70 an exceedingly simple and effective means of accomplishing the desired result. The port c communicates directly with the open air and has not any valve or other device associated therewith.

I am aware that devices have been provided having ports in the side of the angle cock, but these ports, in general, communicate with further valves or cocks, which prevent the free passage to the open air and render the device very liable to become out of 75 order.

While the invention has been described herein, with great particularity of detail, yet it will be readily understood that in carrying 85 out the construction of the same, changes, within the scope of the appended claims, may be made without departing from the spirit of the invention.

It is also important to note that my invention 90 only places one side of the angle cock in communication with the open air. This enables the engineer to still retain control of the forward part of the train, and does not throw the whole system out of operation, as 95 it would, if both sides of the angle cock communicated with the open air. The effect of the operation is to throw the brakes on rear part of the train into operation, which will exert a drag, rendering the immediate 100 rectification of the error necessary.

What I claim as my invention is:

1. In an air brake system, the combination including a plug having a passageway

therethrough, and a port in the side of the passage-way, a casing inclosing the plug having a port therein gradually enlarged in the direction of rotation of the plug.

5 2. In an air brake system, the combination including a plug having a passageway therethrough, and a port in the side of the passage-way, a casing inclosing the plug hav-

ing a triangular port therein gradually enlarged in the direction of rotation of the plug. 10

In witness whereof I have hereunto set my hand in the presence of two witnesses.

JAMES FALLON.
